HEATED HAND-COVERING

Robert M. Eisendrath, Chicago, Ill.

Application April 10, 1933, Serial No. 665,418

1 Claim. (Cl. 2—158)

The invention relates to hand coverings as mittens or gloves and has as an object the provision of such an article of apparel having means for heating the hand of the wearer.

5 It is a further object of the invention to provide an article of this class wherein the heating means may be carried indefinitely in inoperative condition but may be promptly brought into operation at any place even though remote from a 10 source of extraneous heat.

It is a further object of the invention to provide an article of the class described that may be worn in positions exposed to rain, in condition of inoperation of the heating means but by reversal 15 of the heating element may be brought into action by the wetting of the apparel by rain.

It is a further object of the invention to provide an article of the class described wherein the degree of heat evolved may be controlled when 20 worn exposed to moisture.

Further objects of the invention will appear from the following description when read in connection with the accompanying drawing showing an illustrative embodiment of the invention, 25 and wherein:—

Fig. 1 is a plan view of a mitten embodying the invention;

Fig. 2 is a side elevation partly broken away; and

30 Fig. 3 is a perspective view of a heating element partly broken away.

As shown the invention is embodied in a mitten 10 although it will be understood that it is equally applicable to any other type of hand covering.

35 For purposes of the invention the mitten is shown as formed with a lining 11 and an outer layer 12 of leather or the like. Beneath the outer layer 12, there is shown a layer 13 desirably formed of a waterproof material as a high grade 40 of rubber to form a pocket, limited by the row of stitching 14, the pocket terminating adjacent the wrist portion in a line of stitching 15. Any desirable means may be provided to form a closable opening for the pocket. As shown the opening 16 45 is held closed by means of a zipper fastening having a slidable element 17.

A heating element 18 of a well known chemical type may be placed in the pocket and may reside therein indefinitely in inoperative condition but 50 ready to be brought into action at any time and at any place without provision of extraneous heat in a well known manner, as by wetting.

The heating element 18 for purposes of the invention is preferably formed upon one side 19 55 of water-proof material and upon the remaining

side 20 of water-permeable material. Thus by removal of the heating element 18 from the pocket, and application of a small quantity of water to the side 20 of the casing thereof, the heating element may be brought into action and 60 replaced in the pocket to warm the hand of the user.

By virtue of the fact that one side of casing of the heating element is formed of waterproof material, this side may be placed upward in contact with the shell 13 of the mitten and even though the device is worn in the rain so that the mitten becomes wet, the heating element will remain inoperative. However if it is desired to have the heating element become operative 70 automatically when worn in the rain, the side 20 may be turned outward in the pocket and the moisture seeping through the portion 13 of the mitten and the side 20 of the heating element will automatically bring the element into action. 75 So worn, if the hand covering becomes too wet, the element particularly when new may cause too high a degree of heat. In such a case the element may be withdrawn from the pocket to bring the waterproof side 19 to the exterior, 80 whereupon additional moisture is prevented from entering the heating element and the heat can thereby be controlled.

The manner of forming the pocket limited by stitching 14, 15 as shown with the inner portion 85 11 extending entirely across the mitten from the seam 21 to the seam upon the opposite edge of the mitten makes the pocket unobtrusive and the appearance of the hand covering is not damaged by the presence of the pocket. 90

The use of the fleece lining 11 has the effect of tempering the heat of the heating element as applied to the skin of the wearer.

By the combination of the chemical heating element with the hand covering, it is possible 95 to provide wearing apparel of this character which may be worn indefinitely with the heating element inoperative but ready at all times to be brought into operation in the simplest manner. The heating element may be very 100 cheaply and readily renewed when exhausted and in use will keep the hand of the wearer warm for hours at a time.

Minor changes may be made in the physical embodiment of the invention within the scope 105 of the appended claim without departing from the spirit of the invention.

I claim:

A device of the class described comprising, 110 in combination: a hand covering; a pocket car-

ried thereby formed of water-impermeable material upon its side adjacent the hand of a wearer; said covering and pocket structure formed with a water-permeable portion from the outer 5 surface of the covering to the interior of the pocket; a chemical heating element susceptible of being brought into action by access of moisture thereto carried in said pocket; said element comprising a casing formed on one side

10

of water-impermeable material and of water-permeable material upon at least a portion of the remaining side; whereby water seeping into the pocket through the hand-covering may be excluded from or admitted to the chemical contents of the heater depending upon its position of reversal in the pocket.
